PROJECTION MAGNIFIER

John T. Armbruster, Niagara Falls, N. Y., assignor to
American Optical Company, Southbridge, Mass., a voluntary association of Massachusetts

Application June 27, 1955, Serial No. 36,687

Term of patent 14 years

(Cl. D61—1)

Fig. 1 is a perspective view of a projection magnifier in a raised position, showing my new design;

Fig. 2 is a similar perspective view in a lowered position but from the opposite corner of the instrument.

The characteristic features of the new design reside in the portions shown in full lines in the drawing.

I claim:

The ornamental design for a projection magnifier, substantially as shown and described.
